UNITED STATES PATENT OFFICE

2,498,144

HYDRAULIC SNOW SHOVEL

Peter Thomas, Augusta, Maine

Application January 29, 1948, Serial No. 5,095

4 Claims. (Cl. 214—78)

1

This invention relates to a hydraulic shovel and is especially adapted for use with shoveling snow and loading it on trucks.

An object of the invention, therefore, is to provide a device that is capable of handling any kind of snow, dirt or loose gravel.

A further object of the invention is to provide hydraulic means capable of effecting the efficient operation of the device.

A still further object is to provide shock absorbing means to arrest the travel of the shovel, as well as return it to virtually vertical position when it has been emptied.

Another object of the invention is to provide latching means on said shovel to automatically return the shovel to operative position after being emptied, as well as means to actuate the latching means.

And still another object of the invention is to provide means to quickly mount and remove the arms and shovel.

It is also the purpose of the invention to produce a simple and inexpensive device and yet one which is very effective in operation.

In addition to the above, this invention comprehends improvements in details of construction and arrangement of parts to be hereinafter described and set forth in the claims.

In the following drawings, in which similar and corresponding parts are designated by the same reference characters throughout the several views:

Figure 1 is a side elevation of a truck illustrating the invention;

Figure 2 is a top plan view of Figure 1;

Figure 3 is an enlarged view of the hydraulic means;

Figure 4 is a detail view partly in section, of the shovel latching means;

Figure 5 is a section taken on line 5—5 of Figure 1, and

Figure 6 is a top plan view of Figure 1 to show the shock absorbing means on the truck.

Figures 7 and 8 are enlarged fragmentary horizontal sectional views of the automatic trip and differential means shown at the left top and bottom of Figure 1.

Referring to Figures 1 and 2, a truck is indicated generally at 10 and includes the usual body portion 12, cab section 14, engine 16, and supporting frame 18. Transmission 20 connects by universal joint 22 to a dump pump (not shown) and by universal joint 24 to a drive shaft 26, which, in turn, connects to a shovel pump 28 by means of universal 30. Pump 28 is, in turn, con-

2

nected to an hydraulic unit 32 which includes a piston rod 34. Piston 34 is pivoted at 35 to a pair of links 36 connected at their upper ends at 37 and at their lower ends to a pair of side plates 38 by means of a transverse pin 40. Side plates 38 are bolted or otherwise suitably secured to the frame of the truck as shown at 42. (See Figure 5.) Pivoted to the upper end of links 36 are a pair of connecting links 44 which, in turn, are pivotally connected by means of a transverse pin 46 to a pair of parallel cranks 48 on a rotatable cross shaft 50. A transverse rod 52, connected at opposite extremities to a pair of parallel beams 54, 56, suitably connected to truck frame 18, serves to support the hydraulic unit 32.

As best seen in Figures 1 and 2, cross shaft 50 is rotatably mounted in suitably lubricated bearing sleeves 58. Mounted on each end of cross shaft 50 by means of apertured plate 60 are a pair of shovel arms 62. Bolts 64 pass through one end of arms 62 and plates 60 to secure them for ready mounting and disassembly. Arms 62 extend beyond the width as well as beyond the forward end of the truck, as can plainly be seen in the figures, and pivotally connect at 66 a shovel 68 at the forward end.

As is clearly shown in Figures 2 and 4, a suitable housing indicated generally at 70, is welded to shovel 68 and provides the automatic tripping means of the invention. A housing 72 includes expansion spring 74 which encloses a guide rod 76 mounted at the lower end of a slide bar 78. Slide bar 78 extends beyond housing 72 and terminates in an enlarged generally triangularly shaped head 80 which is forked at its mid-point 82. A rod 84 extends transversely between shovel arms 62 and is welded thereto. Fork 82 engages rod 84 for locking engagement therewith. A U-shaped operating control mechanism 86 includes a transverse pin 87 extending through rod 84, a pin 88 connected to an ear of control 86 and a rope 90. Rope 90 is pivotally connected to control 86 and is trained around a pulley 92 mounted on plate 60 and extends across the bottom of cab 14 to a point adjacent the operator for actuation (not shown).

Thus, it becomes quite simple to empty the shovel, and the operator merely pulls the rope 90 to release the latching means. An actuating bar 94 is mounted on bar 78 and stops forward or backward movement at head 80 by engaging either lip 96 or 98, respectively, on housing 72. Control mechanism 86 is also adjustable to equalize release on the shovel and thus prevent one side from releasing before the other. This is ac-

complished by means of ear 100 pivotally engaging mechanism 86 at one end and transverse pin 87 at the other extreme to move arcuate pin 102 in unison with pin 88. Rod 84 is made up of two sections 104 and 106 fitting into a larger pipe or sleeve 108 and is held in position by means of pins 110, 112. It thus becomes a simple matter to quickly remove the arms and shovel when so desired, by merely removing pins 110, 112. A spring bumper 114 is mounted on the side of body portion 12 of the truck, by means of bracket 116, and includes a housing 118 within which is positioned an expansion spring 120, which urges a bumper rod 122 outwardly. A shock absorbing pad or seat 124 is mounted on rod 122. As is best seen in Figure 6, two shock absorbing means 114 are employed and are mounted, one on each side of the truck body, so that seats 124 each receive an arm 62 of shovel 68 when the latter is in dump position. Seats 124 are arcuate or concave in shape and thus assist in keeping arms 62 parallel to each other in the event one or both tend to shift sideways. Mounted on rods 122 are sleeves 132 to removably retain, by means of pins 134, seats 124. Rods 126, on actuation move into housing 118 through opening 136, and return shovel 68 to vertical position when the scoop is emptied. The shovel, when swung back over the truck with a full load, is thus limited in movement, as well as properly aligned at all times.

From the above description, the operation of the device is readily apparent. In operation, the truck 10 is moved forward under its power and snow, or other material on the ground, is gathered into scoop 68. When the latter is full, pump 28 will operate hydraulic cylinder 32 to raise shovel 68 into the position shown in dotted lines in Figure 1. In addition, to assist in pulling the shovel over its center of gravity, a spring 126 engages cross shaft 50 at 128 and is fixed to frame 18 at 130. When the shovel has been raised, it is brought to a stop by means of spring bumper 114, arms 62 seating in the arcuate portion 124. The operator then draws on rope 90 to release the latching means 70 and allows scoop 68 to trip over backwards to empty. The shovel is then returned to the ground by reverse actuation of the hydraulic control, and as the shovel nears the ground, it is automatically latched for reloading.

While the specification sets forth in detail the present and preferred construction of the device, it is to be understood that deviations may be resorted to as do not form a departure from the

spirit of the invention as defined by the appended claims.

Having described the invention, what is claimed as new is:

1. A loading device for a truck including a crankshaft journaled in a truck frame, a pair of side arms extending forward beyond the truck and secured to the end portions of the crankshaft, a shovel carried between said arms, and tension means on said shovel to releasably lock it on said arms, said tension means including a latch housing welded on said shovel, a spring mounted in said housing, a slidably stop bar connected to said spring at one end and a pin extending through said side arms and engaging said stop bar at its free end.

2. A loading device for a truck including a crankshaft journaled in a truck frame, a pair of side arms extending forward beyond the truck and secured to the end portions of the crankshaft, a shovel carried between said arms, tension means on said shovel to releasably lock it on said arms, and means to adjust said tension means to equalize the action of said shovel.

3. A loading device for a truck including a crankshaft journaled in a truck frame, a pair of side arms extending forward beyond the truck and secured to the end portions of the crankshaft, a shovel carried between said arms, and a pair of shock absorbing means mounted on each side of said truck to stop the movement of said shovel, each of said shock absorbing means including an expansion spring, a bumper rod mounted on said spring, and a saddle seat on the other end of said bumper rod, said seat including upwardly extending, outwardly tapering ears for seating of the shovel arms.

4. The combination of claim 3, wherein said saddle seat is removably connected to said bumper rod.

PETER THOMAS.
